UNITED STATES PATENT OFFICE.

JACOB DARRE JENSSSEN, OF NEW YORK, N. Y., ASSIGNOR TO G. D. JENSSSEN COMPANY, OF NEW YORK, N. Y.

APPARATUS FOR MAKING BISULPHITE LIQUOR.

Application filed May 4, 1927, Serial No. 188,737, and in Canada September 23, 1926.

The invention relates to an apparatus for making bisulphite liquor, as described in the present specification and illustrated in the accompanying drawings that form part of 5 the same.

The invention consists essentially of the novel features of construction pointed out broadly and specifically in the claims for novelty following a description containing an 10 explanation in detail of an acceptable form of the invention.

The objects of the invention are to furnish means for regulating the flow of gas and water to and from the towers; to form a 15 method whereby the flow of gas and water may be reversed if desired; to construct an apparatus for the purpose of gas absorption processes and the like in which the continuous operation need not be interrupted in the ordinary course of events; to regulate the percentage of free sulphur dioxide in the finished acid liquor and generally to provide a plant showing an efficient circulation system of the gas and liquor that may be readily reversed 20 from time to time and that will utilize the sulphur gas to the very best advantage in the production of the finished acid liquor.

In the drawings, Figure 1 is a vertical sectional view of the towers showing the various 25 connections.

Figure 2 is an enlarged sectional detail in perspective of the four way valve as used in this invention.

Figure 3 is a plan view partly in section of 30 the four way valve.

Figure 4 is a vertical sectional view of the six way acid cock.

Figure 5 is a plan view partly in section of 35 the six way acid cock.

Like numerals of reference indicate corresponding parts in the various figures.

Referring to the drawings, the towers 10 and 11 form part of a circulation system through the upper and lower gas pipes 12 and 40 13 and 14 and 15 respectively, the flow of gas being directed in regard to the upper gas pipes 12 and 13 by the four way valve 16, and the flow of gas in regard to the lower gas pipes 14 and 15 being directed by the four 45 way valve 17. These two valves 16 and 17 are connected by the gas pipe 18.

The lower valve 17 is connected to the gas inlet pipe 19, which is connected to a sulphur burner, and the upper valve 16 leads to the

exhaust pipe 20 to the atmosphere and extending upwardly from said valve 16.

Each of the four way valves 16 and 17 comprise the valve plate 21 made integral with the end circular plates 22 and 23, the circular plate 22 having the projecting lug 24 secured in the bearing 25 in the stationary plate 26 and having the indicator 27 adapted to be moved between the two indicator lugs 28 and 28^a, this plate 26 being secured to the housing 29 of the valve.

The apparatus is here shown with two towers 10 and 11, though this invention is not limited to any particular number so long as the salient features are included. A quantity of limestone in pieces customarily used in such processes is supported in the tower 10 on the upper grate 30 and in the tower 11 on the upper grate 31 and above the limestone in the tower 10 the spray box 32 is situated and similarly in the tower 11 the spray 33.

The lower grates 34 and 35 are situated in the towers 10 and 11 respectively at reasonable distance above the bottom and spaced from the grates 30 and 31 and support the blocks of hard wood, tile, rings or other insoluble material which fill up the greater part of the space between the upper and lower grates.

The water inlet pipe 36 connected to a suitable source of water supply feeds through a six way acid cock 37, comprising the valve 38 formed of the plates 39 and 40 and 41 in angular formation in relation to one another and integral at each end with the circular rotatable plate 42 and 43 and contained in a housing 44. One of the rotatable plates 42 has a projecting lug 45 extending through the hole 46 in a removable cover 47 and this lug 45 is secured to the indicator lever 48, said indicator 48 being movable between two stop lugs 49 and 50. The removable cover 47 has the projecting crown 51 adapted to engage between the housing 44 and plate 42, and having the packing 53 and 54, and is adapted to be bolted by a plurality of bolts 55 to the housing 44.

From this six way acid cock, the pipes 57 and 58 are connected to the water pumps 59 and 60, the pipes 61 and 62 are connected to the towers 10 and 11 respectively, the pipe 63 is connected to the acid storage tank 64, and the pipes 65 and 66 are connected to the towers through the pumps 59 and 60.

In one form of operating of the apparatus, the gas flows through the inlet pipe 19 into the valve 17, through the pipe 15 into the tower 11 and upwardly therein and out therefrom through the pipe 13 through the valve 16 and down the pipe 18 to the valve 17 and through the pipe 14 into the tower 10, upwardly therein, and out through the pipe 12 and through the valve 16 to the exhaust pipe 20 to the atmosphere.

The water enters the six way acid cock and from there flows into the pump 60 by the pipe 58 and upwardly through the pipe 66 to the top of the tower 10 and thereinto and the weak acid liquor flows out through the pipe 61 to the acid cock and from there through the pipe 57 into the pump 59 and as weak acid liquor enters the tower 11 through the pipe 65, then strong acid liquor flows through the pipe 62 back to the acid cock and through the pipe 63 to the acid storage tank 64.

It will be of course understood that if it is desired, the direction of the circulation may be reversed, that is to say, that the gas may be fed from the top and the water from the bottom in the form of a spray or other means, and also that the direction of the gas in the gas pipes may be reversed and making the tower 11 the strong acid liquor and the tower 10 the weak acid liquor, without departing in any way from the main features of the invention.

What I claim is:—

1. In an apparatus for making bisulphite liquor, a circulation system comprising a plurality of towers having gas inlets and outlets and water and liquor inlets and outlets and piping from all of said inlets and outlets and from the water supply and to the atmosphere, four-way valves introduced in the gas connections having rotary deflecting plates adapted to reverse the direction of the circulation and indicators therefrom and a six-way valve having rotary deflecting plates and indicators therefrom and introduced in the liquid connections.

2. In an apparatus for making bisulphite liquor, a plurality of acid liquor towers having upper gas openings and lower gas openings, transverse and vertical gas pipes connecting said openings, four-way valves introduced at the junctions of said vertical and transverse pipes and having rotary plate deflecting members and stems therefrom carrying indicators in respect to the direction of circulation, a six-way valve having angularly set deflecting plates and a stem therefrom and an indicator on said stem set in agreement with the aforesaid indicators, water and liquor pipes to and from said six-way valve and connected to said towers, and to a storage tank and pumps elevating water and liquor to said towers.

3. In an apparatus for making bisulphite liquor, a plurality of towers and piping for

a circulation system of gas and liquid in varying directions, four-way valves introduced in said system and comprising housings enclosing rotary plates journaled in said housings and carrying deflecting plates and having stems therefrom operating between stops and a distributing member in the form of a six-way valve cock comprising a housing, circular plates journaled in said housing and deflecting plates rigidly secured to said circular plates in angular arrangement to one another and adapted to form passages in each instance between an inlet and an outlet, said plates forming a rotary valve directing the course of the water and liquor in one direction or the other in agreement with the setting of the four-way valves and having a stem carrying a direction indicator operating between stops.

4. An apparatus for making bisulphite liquor, comprising a weak acid liquor tower and a strong acid liquor tower, each having upper and lower gas feed pipes and upper and lower water pipes, valves having a common connection to one another and a direct gas feed connected to one valve and an atmosphere pipe connected to the other valve, each of said valves having a plate made integral with end circular plates, one of said circular plates having a projecting lug inserted through a stationary plate and having an indicating lever secured thereto and adapted to be moved between stop lugs in said stationary plates, and casing for said valves, an acid cock connected to a source of water supply and having pipes connected to suitable pumps, and water pipes connected to said pumps and to said towers, and water pipes from said towers to said acid cock.

5. An apparatus for making bisulphite liquor, comprising a weak acid liquor tower and a strong acid liquor tower, each having upper and lower gas feed pipes and upper and lower water pipes, valves having a common connection to one another and a direct gas feed connected to one valve and an atmosphere pipe connected to the other valve, each of said valves having circular rotatable plates connected together by horizontal plates and enclosed in a suitable casing, an acid cock having a plurality of plates made integral with one another and forming a part of end circular plates and a suitable casing enclosing the same, said acid cock being connected to a source of water supply and having pipes connected to suitable pumps, and water pipes connected to said pumps and to said towers, and water pipes from said towers to said acid cock.

6. An apparatus for making bisulphite liquor, comprising a weak acid liquor tower and a strong acid liquor tower, each having upper and lower gas feed pipes and upper and lower water pipes, valves having a common connection to one another and a direct

- gas feed connected to one valve and an atmosphere pipe connected to the other valve, each of said valves having circular rotatable plates connected together by horizontal plates and 5 enclosed in a suitable casing, an acid cock having a plurality of plates made integral with one another and forming a part of end circular and rotatable plates, one of said circular plates having a projecting lug inserted 10 in a bearing of a removable cover and having an indicating lever secured thereto and adapted to be moved between stop lugs in said cover, and a casing enclosing said valves, said acid cock being connected to a suitable 15 source of water supply and having pipes connected to a suitable pump, and water pipes connected to said pumps and to said towers, and water pipes from said towers to said acid cock.
- 20 7. An apparatus for making bisulphite liquor, comprising a weak acid liquor tower and a strong acid liquor tower, each having upper and lower gas feed pipes and upper and lower water pipes, valves having a common connection to one another and a direct gas feed connected to one valve and an atmosphere pipe connected to the other valve, each of said valves having circular rotatable plates connected together by horizontal plates and 25 enclosed in a suitable casing, an acid cock 30 having a plurality of plates made integral with one another and forming a part of end circular rotatable plates, one of said circular plates having a projecting lug inserted in a bearing of a removable cover, said removable 35 cover having a projecting crown adapted to engage between the circular plate and casing and having suitable packing, said acid cock being connected to a source of water supply and having pipes connected to suitable 40 pumps, and water pipes connected to said pumps and to said towers, and water pipes from said towers to said acid cock.

Signed at New York this 26th day of March, 1927.

JACOB DARRE JENSSEN.
